(57) **CLAIM**

The ornamental design for a radiofrequency skin device, as shown and described.

DESCRIPTION

FIG. 1 is a perspective view of the radiofrequency skin device in accordance with the present design;

FIG. 2 is a front view of the radiofrequency skin device in accordance with the present design;

FIG. 3 is a back view of the radiofrequency skin device in accordance with the present design;

FIG. 4 is a right view of the radiofrequency skin device in accordance with the present design;

FIG. 5 is a left view of the radiofrequency skin device in accordance with the present design;

FIG. 6 is a top view of the radiofrequency skin device in accordance with the present design; and,

FIG. 7 is a bottom view of the radiofrequency skin device in accordance with the present design.
